COLLAR-BUTTON

Otto Grotewold, Frankfort-on-the-Main,
GermanyApplication November 3, 1933, Serial No. 696,556
In Germany November 6, 1932

2 Claims. (Cl. 24—61)

The present invention relates to a collar-button the distinctive feature of which is that it serves at the same time as a neck-tie holder.

It is a widely known fact that if ordinary collar-buttons are used, the bound or knotted portion of the neck tie will gradually slip downwards or sideways of the front of the shirt or collar worn, because the friction of the tie against the surfaces of the collar is not sufficient to keep it in place.

The present invention overcomes this disadvantage. According to this invention, a suitably shaped member, as described below, is attached to an ordinary collar button plate. It is provided, at a suitable distance from the button plate, with a downward bend, and is then bent upwards, ending in a relatively elastic point. The downward bend serves to keep the two shirt sides, as well as the two ends of the collar together, while the elastic point extending upwards presses against the neck-tie and holds it against the upper inside edge of the collar. It is impossible, therefore, that the neck-tie could move or slip.

In the accompanying drawing, the invention is shown by way of example; Fig. 1 is a view, partly in section, of the button as actually used on a collar and shirt; Fig. 2 is a side view of the button, whereas Fig. 3 is a top or plan view of the same.

Referring to the drawing, the collar button, including a button plate or disc *a* made of any suitable material has an extending portion. Said portion has bifurcated or pronged shape metallic members *b* consisting of a pair of spaced tines which as shown in Fig. 2, are bent downwardly at *b*₁. Said tines, as seen from the top of the Fig. 3, converge toward each other at *b*₁ and are then bent obliquely upward ending in a relatively elastic end portion or point *c* against which a tie *e* is adapted to rest.

The downwardly bent portion *b*₁ of the tines abuts the opening of the outer piece in the collar *f* and prevents the collar button from sliding inwardly of the collar holes. It is to be noted that a certain amount of clearance is provided between button plate *a* and the portions *b*₁ to ac-

commodate the combined contacting flaps of the collar and shirt.

Protruding elastic point *c* being preferably also of metal extends above the plane of extension of member *b*, thereby affording some resilience to the member when it abuts a tie. The relative elasticity or flexibility of the protruding point *c* reduces the pressure of plate *a* against the throat of the wearer of the collar button when a tie *e* is unduly pressed downward against the button.

As shown in the drawing, the tie *e* remains pressed against the upper inner edge of the collar *f* and is effectively prevented from slipping because of the engaging position of the obliquely bent end portion *c* of the collar button.

While there is described one preferred form of the invention taken in connection with the accompanying drawing, in which the various parts are preferably of metal either integral or joined together in any suitable manner, it is to be understood that various changes may be made as to form, use and materials without departing from the spirit and scope of the invention as defined in the appended claims.

I claim:

1. An integral collar button comprising a button plate, a bifurcated member extending perpendicularly from the central portion of said plate having a downward, acutely bent portion in which the bifurcations of said member converge, and an obliquely, upward extending, straight end portion in connection with the downwardly bent converging portion, forming a relatively resilient end in alignment with the plane of the perpendicularly extending portion of the member.

2. An integral collar button for supporting a shirt tie knot including, a button plate, a pair of equi-spaced tines extending from the central portion of said plate, each having a downwardly acutely bent portion, each tine converging toward the other, and an obliquely upwardly extending converging portion merging together, forming a terminal for retaining a tie knot in fixed position when worn against a shirt collar.

OTTO GROTEWOLD.
